(57) **CLAIM**

The ornamental design for a mountable light, as shown and described.

DESCRIPTION

FIG. 1 is a top front left side perspective view of a mountable light according to our design;

FIG. 2 is a top rear left side perspective view of the mountable light shown in FIG. 1;

FIG. 3 is a bottom rear right side perspective view of the mountable light shown in FIG. 1;

FIG. 4 is a bottom front right side perspective view of the mountable light shown in FIG. 1;

FIG. 5 is a front view of the mountable light shown in FIG. 1;

FIG. 6 is a left side view of the mountable light shown in FIG. 1;

FIG. 7 is a rear view of the mountable light shown in FIG. 1;

FIG. 8 is a right side view of the mountable light shown in FIG. 1;

FIG. 9 is a top view of the mountable light shown in FIG. 1;

FIG. 10 is a bottom view of the mountable light shown in FIG. 1.

FIG. 11 is a right side view of a mountable light tilted at an angle relative to a vertical direction according to our design;

FIG. 12 is a top front right side view of the mountable light oriented in a horizontal orientation according to our design; and,

FIG. 13 is a bottom front left side perspective view of the mountable light that is oriented in a horizontal orientation according to our design.

The dashed lines shown in the drawings depict portions of the mountable light and also portions of the environment of the mountable light that form no part of the claimed design.

1 Claim, 12 Drawing Sheets
